(57) **CLAIM**

The ornamental design for a forklift pad, as shown and described.

DESCRIPTION

FIG. 1 is a top perspective view of a forklift pad showing a flattened pocket for receiving a fork showing my new design;

FIG. 2 is a bottom perspective thereof;

FIG. 3 is a top view thereof;

FIG. 4 is a front view thereof, the rear view being a mirror image of the front view;

FIG. 5 is a left side view thereof;

FIG. 6 is a right side view thereof;

FIG. 7 is a bottom view thereof;

FIG. 8 is a front view thereof showing the pocket open, the rear view being a mirror image of the front view;

FIG. 9 is a left side view thereof;

FIG. 10 is a right side view thereof;

FIG. 11 is an environmental view thereof; and,

FIG. 12 is an environmental view thereof with the pocket flattened.

The broken lines shown in the figures are for the purpose of illustrating portions of the forklift pad, which form no part of the claimed design. Additional dash-dot broken lines in FIGS. 11 and 12 show environment and form no part of the claimed design.
